CLOCK

Robert O. Fletcher, Ashland, Mass., assignor to General
Electric Company, a corporation of New York

Application January 7, 1954, Serial No. 28,403

Term of patent 14 years

(Cl. D42—7)

Fig. 1

Fig. 3.

Fig. 2

To all whom it may concern:

Be it known that I, Robert O. Fletcher, have invented a new, original, and ornamental Design for a Clock, of which the following is a specification, reference being had to the accompanying drawing, forming a part hereof.

In the drawing,

Fig. 1 is a front perspective view of a clock embodying my new design.

Fig. 2 is a side elevational view.

Fig. 3 is a front elevational view.

The dominant features of the design reside in the portions shown in full lines.

I claim:

The ornamental design for a clock, as shown and described.
